COLLAPSIBLE TOY BUILDING

Florence A. Olson, Janesville, Wis.

**Application October 24
1. Claim.**

1. *Introduction*

1. Claim 1 (Cl. 20-28)

This invention relates to new and useful improvements in structural refinements in toys, and the principal object of the invention is to provide a toy building in the form of a church, this being sufficiently large to accommodate a child, but being collapsible to a compact folded position so that it may be conveniently stored away when it is not in use.

An important feature of the invention therefore, resides in the collapsible structure of the toy building, while some of the features of the invention lie in its simplicity, in its pleasing appearance, in the highly entertaining nature of its use, and in its adaptability to economical manufacture.

With the above more important objects and features in view, and such other objects and features as may become apparent as this specification proceeds, the invention consists essentially of the arrangement and construction of parts as illustrated in the accompanying drawings, in which:

Figure 1 is a front perspective view of the invention in its erected position;

Figure 2 is a rear perspective view thereof;

Fig. 3 is a front perspective view, similar to that shown in Figure 1, but illustrating the superstructure of the building as being swung rearwardly as the initial step in the collapsing operation;

Figure 4 is a perspective view of the invention in its folded position;

Figure 5 is a cross sectional view, taken substantially in the plane of the line 5-5 in Figure 1; and,

Figure 6 is a cross sectional view, taken substantially in the plane of the line 6-6 in Figure 4.

Like characters of reference are employed to designate like parts in the specification and throughout the several views.

Referring now to the accompanying drawings in detail, the invention consists of a collapsible toy building, designated generally by the reference character 10, this embodying in its construction a substantially rectangular, hollow base portion 12 and a hollow superstructure 14, the base portion 12 consisting of a front wall 16, a rear wall 18, a pair of spaced side walls 20 and top and bottom walls 22, 24 respectively, the rear edges of the top and bottom walls being spaced forwardly from the rear wall 18 so as to provide an opening 26 in the top and a similar opening 28 in the bottom of the base portion, as is best shown in Figure 5.

Side edges 22' of the top wall 22 are secured

to the side walls 20 and a reinforcing angle 23 is mounted on the contiguous edge portions of the top and front walls, whereby the top wall is firmly supported in a horizontal position.

5 In addition, it is to be noted that side wall extensions 30 constitute upward continuations of the side walls 20 and are hingedly connected thereto as at 32, it being understood that the entire building is preferably constructed of foldable and distortable material such as card board or the like, so that the hinge connection 32 may simply assume the form of fold lines, permitting the side wall extensions 30 to be folded inwardly upon the top wall 22.

15 The superstructure 14 includes a back panel 34 which, in effect, constitutes an upward continuation of the rear wall 18 to which it is hingedly connected by a transverse fold line 36, while a pair of side panels 38 extend forwardly
20 from the back panel 34, as shown.

When the invention is placed in use, the superstructure 14 is maintained in an erect position by engaging the lower edges 40 of the side panels

38 with the rear edge portion of the top wall
25 22 of the base portion 12, while the side wall
extensions 30 are disposed exteriorly of the side
panels 38 and are thus maintained by the erected
superstructure in an upstanding position, as
illustrated in Figures 1, 2 and 5. In this posi-
30 tion, a child may seat himself in the building,

the top opening 32 establishing convenient communication between the interior of the superstructure and the interior of the base portion, while the top wall 22 itself constitutes a con-

35 venient table top for supporting a removable book rest 42. It may be explained at this point that to provide a realistic effect, the side walls 20 and extensions 30 as well as the rear wall 18 and rear panel 34 may be painted with representations of windows as exemplified at 44, while a miniature bell 46 may be suspended from the arched side panels 38 as shown in Figure 1.

When it is desired to fold the building, the superstructure 14 is first swung or tilted rearwardly as indicated at 48 to the position indicated by the dotted lines 50 in Figure 5, this action permitting the side wall extensions 30 to be folded inwardly on the top wall 22 as indicated at 52 in Figure 3. The side panels 38 of the superstructure 14 may then be spread apart and the superstructure swung forwardly as at 54 to a substantially horizontal position indicated at 56 in Figure 5, so that the panels 38 are disposed outside the side walls 20 and virtually the entire base portion 12 is accommodated in the interior of the superstructure, as shown in

Figure 4. It will be apparent that in this position the invention may be conveniently stored when it is not in use.

It is believed that the advantages and use of the invention will be clearly understood from the foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

A collapsible toy building formed from foldable and distortable sheet material and comprising in combination, a hollow base portion including a front wall, a rear wall, a pair of side walls connected at front and rear edges thereof to the respective front and rear walls, a top wall rigidly affixed to the upper edge of the front wall and to upper edge portions of the side walls and having its rear edge spaced forwardly from said rear wall whereby to provide an opening in the top of said base portion, a pair of inwardly foldable side wall extensions

provided at the upper edges of the respective side walls, and a hollow superstructure including a swingable rear panel hinged to the upper edge of the rear wall, and a pair of forwardly extended side panels connected to opposite side edges of the rear panel, said side panels being wider than the space between the top and the rear walls, lower edge portions of said side panels resting on said top wall whereby to sustain said superstructure in an erect position wherein said side wall extensions are disposed at the outer surfaces of and against said side panels, said rear panel being swingable rearwardly and said side panels being adapted to be spread 15 apart whereby the side wall extensions may be folded inwardly and received within the side panels on said top wall to permit the superstructure to be swung forwardly on the folded side wall extensions and accommodate the base 20 portion therein.
